MACHINE COMPANY, OF TORRINGTON, CONNECTICUT, A CORPORATION.

BELT-SHIFTING MECHANISM.

1,252,350.

Specification of Letters Patent.

Patented Jan. 1, 1918.

Application filed December 18, 1916. Serial No. 137,434.

To all whom it may concern:

Be it known that I, GEORGE H. KNIGHT, a citizen of the United States, residing at Torrington, in the county of Litchfield and State of Connecticut, have invented a new and useful Improvement in Belt-Shifting Mechanism; and I do hereby declare the following, when taken in connection with the accompanying drawings and the characters 10 of reference marked thereon, to be a full, clear, and exact description of the same, and which said drawings constitute part of this application, and represent, in—

Figure 1 a broken view in front elevation 15 of my improved belt-shifting mechanism, the tubular shaft employed to connect the upper and lower units of the mechanism being centrally broken away.

Fig. 2 a corresponding view in side elevation.

Fig. 3 a sectional view on the line 3—3 of Fig. 1, looking upward.

Fig. 4 a sectional view on the line 4—4 of Fig. 1, looking downward.

Fig. 5 a broken view corresponding to Fig. 3, showing the canting of the belt-shifting lever of the upper unit of the mechanism as the result of the first turn of the operating-handle in shifting the belt for reducing 30 the speed.

Fig. 6 a broken view corresponding to Fig. 4, and showing the belt-shifting lever of the lower unit of the mechanism canted as the result of the first turn of the operating handle in shifting the belt for reducing the speed.

Fig. 7 a detached plan view of the bevel gear of the lower unit of the mechanism.

My invention relates to an improved belt-shifting mechanism for use in conjunction with shapers, lathes, drills, boring mills, wood-working machinery, et cetera, the object being to produce a simple, compact and reliable mechanism constructed with particular reference to quickness and ease of operation, and the reduction of belt-wear to the minimum.

With these ends in view, my invention consists in a belt-shifting mechanism characterized by provision for positively twisting the belt to cause its advancing edge to swing outward with respect to the cone preparatory to shifting it, and having certain details of construction and combinations of

parts as will be hereinafter described and 55 pointed out in the claims.

In carrying out my invention as herein shown, I employ an inclined operating-handle 5 pinned to the outer end of a short shaft 6 journaled in an inclined arm 7 formed integral with, and offsetting from a globular gear-case 8 formed with a tubular standard 9 made integral with the upper face of a sliding carrier 10 mounted upon the cam-plate 11 of the lower unit of the mechanism. 65 As shown, the edges of the said plate are beveled for the retention of the carrier in place as the same slides back and forth upon the plate.

The inner end of the shaft 6 is furnished 70 with a bevel pinion 12 meshing into a bevel gear 13 located within the gear-case 8 and fixed upon the upper end of a vertical shaft 14 extending downward through the said tubular standard 9, and at its lower end carrying a rack pinion 15 meshing into a rack 16 secured to the under face of the said cam-plate 11 which is positioned so as to follow the tapering outline of the stepped lower cone which, as shown, has four steps 17, 18, 75 19 and 20. The said stepped cone is located within a tapering cone-casing 21 secured to the machine-frame 22. The cone itself is mounted upon a driven shaft 23. A bracket 24 applied to the outer or smaller end of the cone-casing 21, is employed for supporting the outer end of the cam-plate 11 the inner end of which is supported upon the cone-case cover 25.

The sliding-carrier 10 aforesaid, has pivotally mounted upon its upper face, a belt-shifting lever 26 swinging upon a stud 27 and furnished at its outer end with an eye 28 through which the power-transmission belt 29 passes. At its inner end, the said 95 lever 26 has an arm 30 carrying a roller 31 running in a symmetrical zigzag cam-slot or pathway 32 having five bends to produce three oscillations of the lever 26, or one less oscillation than there are steps on the cone. 100 The combined longitudinal movement of the sliding carrier 10 on the cam-plate 11, and the travel of the roller 31 in the zigzag cam-slot or pathway 32, results in the intermittent oscillation and direct or linear movement of the belt-shifting lever 26, whereby the belt 29 is alternately twisted with respect to the steps of the cone, and moved in line 105

therewith, as will be more fully described in due course.

The said bevel gear 13 has an upwardly extending hollow hub 33 formed with oppositely located slots 34, (Fig. 5) receiving the

- projecting ends of a coupling-pin 35 passing transversely through the rounded-head 36 of a universal-joint piece 37 secured by a pin 38 to the lower end of a tubular shaft 39, the upper end of which is connected with the upper unit of the mechanism, the said upper unit substantially duplicating the lower unit already described, but having the steps of its cone reversed in direction.

- 15 A corresponding universal-joint piece 40 is secured by a pin 41 to the upper end of the said shaft 39, the rounded head 42 of the said joint-piece being entered into the depending hollow hub 43 of a rack-pinion 44.

20 corresponding to the pinion 15 already described, the said hub 43 being formed with oppositely located slots 45 for the reception of the projecting ends of a coupling-pin 46 passing through the rounded head 42 of the

25 said universal-joint piece 40.

26 said an eccentric piece 15.
The pinion 44 is mounted upon the lower end of a short vertical shaft 47 journaled in a boss 48 formed integral with the upper face of a sliding-carrier 49 mounted upon 30 the upper cam-plate 50 which corresponds in construction, arrangement and function to the lower cam-plate 11 already described. The said cam-plate 50 is secured at its ends to brackets 51 and 52 mounted upon a rod 35 53 supported at its ends in a pair of arms 54 adjustably secured by bolts 55 passing through segmental slots 56, to the lower ends of counter-shaft hangers 57 carrying a counter-shaft 58 upon which the upper or driving cone is mounted, the said upper cone having four steps 59, 60, 61 and 62 corresponding to the steps 20, 19, 18 and 17, but 40 reversed in arrangement.

The said pinion 44 meshes into a rack 63 secured to the under face of the said cam-plate 50 which is formed with a symmetrical zigzag cam-slot or pathway 64 correspond-
ing to the zigzag cam-slot or pathway 32 in the plate 11, and receiving a roller 65 car-
ried by the arm 66 of a belt-shifting lever 67 mounted upon the upper face of the sliding carrier 49 so as to swing upon a stud 68, the outer end of the said lever 67 being fur-
nished with an eye 69 through which the belt 29 passes. The sliding of the carrier 49 over the cam-plate 50 and the travel of the roller 65 in the cam-slot 44, results in the same canting and direct bodily movement of the lever 67 with respect to the belt 29, as already described, for the lever 26 of the lower unit of the mechanism.

Having now described my improved mechanism in detail, I will set forth the mode of its operation.

- 85 In the drawings the mechanism is shown

as shifted for securing the maximum speed of the driven shaft 23, with the belt 29 running over the step 20 of the lower cone, and the step 62 of the upper cone. If now the operating handle 25 is turned clockwise, 70 (from left to right) one complete turn, the sliding-carriers 10 and 14 will be simultaneously moved to the same extent upon their respective cam-plates 11 and 50, into the positions shown in Figs. 6 and 5 respectively, 75 with the effect of canting the belt-shifting lever 67 inward so as to strip the belt 29 from the step 62 of the upper cone and drop it off onto the adjacent step 61 thereof, whereby the belt is loosened. At the same 80 time the belt-shifting lever 26 is canted outwardly with the effect of twisting the belt 29 so as to spring its inner edge away from the step 20 of the lower cone and outward with respect to the periphery of the step 19 85 of the said cone.

The turning of the handle 5 is continued until it completes a second revolution during which the slides 49 and 10 are simultaneously moved farther inward with the effect of restoring the said levers 67 and 26 into the positions in which they are shown in Figs. 3 and 4 with the exception that they will now be located opposite the steps 61 and 19 of the respective cones. The belt 95 has now been shifted one step on each cone in the direction of reduced speed. To further reduce the speed of the driven shaft 23, the operating-handle 5 is given two or more complete turns, whereby the belt is shifted 100 at the top and twisted and shifted at the bottom in the manner already described, after which the belt will be left running on the steps 60 and 18 of the cones. Two more complete turns of the handle 5, will in the same manner shift the belt to run over the steps 59 and 17 of the two cones, whereby the shaft 23 will be driven at its lowest speed.

Now to increase the speed of the shaft 23, 110 the handle 5 is given two complete turns counter-clockwise, (left to right), whereby the belt will be shifted outward from the steps 59 and 17 to the steps 60 and 18, and so on until the maximum speed is again 115 reached. In shifting the belt for increasing the speed by turning the handle 5 counter-clockwise, the mechanism shifts the lower end of the belt and twists and shifts the upper end of the belt which is just the reverse 120 of what happens in reducing the speed.

The mechanism can readily be geared so as to require but one revolution of the handle for completing the shifting of the belt one step: or on the other hand, in case of a very heavy belt, the mechanism can be geared so that it will require three, four or more revolutions of the handle to effect the shifting of the belt one step, all this being merely a matter of gearing and having nothing to do 125 180

with my fundamental principle. It will be noted that under my invention, the belt-shifting mechanism is self-contained and positively twists the belt so as to cause its 5 advancing edge to swing outward with respect to the steps of the cones without utilizing them as points of purchase for the adjacent edge of the belt which is mechanically, and thus positively twisted without help 10 from the cones themselves.

It will be seen from the foregoing that my improved mechanism provides for positively twisting the belt to cause its advancing edge to swing outward with respect to 15 the cone before shifting it onto a step of larger diameter, whereby the power necessary to shift the belt is greatly reduced, and the life of the belt prolonged, since when the belt has been twisted, it is very easily 20 guided from one step to a step of larger diameter. The mechanism will be constructed so that the twist produced in the belt will always take place where it runs onto the steps of the cones rather than where 25 it leaves the steps.

I would have it understood that I do not limit myself to the particular construction shown and described, since various instrumentalities might be employed for positively twisting the belt to cause its advancing edge to swing outward with respect to the cone during the operation of shifting it. Thus, other means than those shown might 30 be employed for operating the sliding-carriers, and the mechanism might be arranged 35 to have the shifting on the overhead cone precede, to some extent, the twisting of the belt on the lower cone, or vice versa. The shifting and twisting of the belt need not 40 be simultaneous, though the twisting of the belt must precede the final shifting.

I claim:

1. In a belt-shifter, the combination with two stepped cones for the reception of a 45 power-transmission belt, of two self-contained belt-shifting mechanisms respectively located adjacent to the said cones and each mechanism being constructed and arranged to positively twist that portion of the belt 50 adjacent to the complementary cone, without aid therefrom, to cause the advancing edge of such portion of the belt to swing outward with respect to the cone preparatory to shifting the twisted portion of the 55 belt from a cone-step of smaller to one of larger diameter.

2. In a belt shifter, the combination with two stepped cones for the reception of a power-transmission belt, of two sliding carriers, belt-shifting levers pivotally mounted 60 thereupon, means for simultaneously moving the said carriers, and means co-acting with

the said levers for imparting swinging movement to them for positively twisting the belt to cause its advancing edge to swing 65 outward with respect to the cones without aid from the steps thereof.

3. In a belt-shifter, the combination with two stepped cones for the reception of a power-transmission belt, of two sliding-carriers, belt-shifting levers mounted thereupon, means for simultaneously moving the said carriers, and cams co-acting with the levers to effect the positive twisting of the belt to cause its advancing edge to swing 75 outward with respect to the cone prior to shifting it from cone-steps of smaller to larger diameter.

4. In a belt-shifting mechanism, the combination with two stepped cones for the reception of a power-transmission belt, of sliding-carriers, means for simultaneously moving the same, belt-shifting levers pivotally mounted upon the said carriers, and zig-zag cams co-acting with the said levers to 85 cant the same with respect to the cones for positively twisting the belt to cause its advancing edge to swing outward with respect to the cone before shifting it from cone-steps of smaller to larger diameter. 90

5. In a belt-shifting mechanism, the combination with two stepped cones for the reception of a power-transmission belt, of sliding-carriers, means for simultaneously moving the said carriers, shifting-levers 95 pivotally mounted upon the same, and cam-plates arranged in line with the profiles of the stepped cones and containing cam-paths co-acting with the said levers for canting the same to positively twist the belt to cause 100 its advancing edge to swing outward with respect to the cone before shifting it from cone steps of smaller to larger diameter.

6. In a belt-shifting mechanism, the combination with two stepped cones for the reception of a power-transmission belt, of sliding carriers, an operating handle, gearing between said handle and the respective carriers, whereby they are simultaneously moved, belt-shifting levers pivotally mounted upon the respective carriers, and means co-acting with the said levers for swinging them to effect the positive twisting of the belt without aid from the cones to cause its advancing edge to swing outward with respect to the cones. 115

In testimony whereof, I have signed this specification in the presence of two subscribing witnesses.
